ABSTRACT: A system for triggering a strobe lamp at a low light intensity in response to signals which are automatically derived by frequency-division from much higher frequency synchronizing signals. It also includes a circuit which enables the production of a single, very high intensity strobe flash by one of the synchronizing signals in response to activation of associated photographic apparatus.

STROBOSCOPE CONTROL SYSTEM

BACKGROUND OF THE INVENTION

This invention relates to a system for controlling the flashing of a stroboscope lamp continuously or for single-flash photographic purposes.

Known stroboscope control systems include systems for dividing the frequency of the synchronizing signals to a rate within the operating range of the stroboscope lamp. However, they require manual setting of the system to accommodate the diverse range of frequencies within which the synchronizing signals fall. Moreover, there is no known stroboscope control system which includes a circuit that is especially adapted to produce a single synchronized high intensity flash for photographic purposes yet protects associated switches from harm due to passage of a very large current through the lamp.

SUMMARY OF THE INVENTION

A circuit is provided to which external (or internal) synchronizing signals are supplied. This circuit automatically divides the frequency of these input signals to a frequency within the operating range of the lamp. This circuit includes a normally nonconducting switching device controlled by signals applied to two different control electrodes associated therewith. Coupled to the switching device is a timing circuit which charges to a predetermined value in response to current flow through the first switching device. When the synchronizing signals are applied to the first control electrode of the first device, the current flow through it charges up the timing circuit to the predetermined value whereupon it discharges. Means are provided for coupling a signal generated by this discharge to the second control electrode thereby cutting the first switching device off. The output frequency subdivided signal is then applied through switching means to operate the circuit which produces the voltage necessary to trigger the lamp. These output signals may be delayed to any desired point in the rotary cycle of the device under study. When a photograph is to be taken of the device under study, a special high intensity circuit is actuated whose function is to prevent the frequency-subdivided pulses from being applied to activate the trigger circuit until such time as a very high charging capacitor has been completely switched into circuit with the lamp. The first frequency-divided pulse received by the high intensity circuit after the end of the timing cycle starts the operation of a second timing cycle whose beginning causes the production of a pulse which operates to fire the strobe lamp at a very high light intensity.

FIG. 1 is a block and schematic view of an overall stroboscope control system which embodies the invention.

FIG. 2 is a schematic view of one of the components shown in block form in FIG. 1.

FIG. 3 is a schematic view of another of the components shown in block form in FIG. 1.

FIG. 4 is a schematic view of still another of the components shown in the block diagram of FIG. 1.

FIG. 5 is a schematic view of another of the components shown in the block diagram of FIG. 1.

FIG. 6 is a schematic diagram corresponding to one of the blocks shown in FIG. 1.

FIG. 7 is a schematic diagram of one of the blocks shown in FIG. 1.

FIG. 8 is a series of waveforms illustrating the operation of the system shown in FIGS. 1, 3 and 6, the waveforms being lettered to correspond to similarly lettered parts of FIGS. 3 and 6.

OVERALL SYSTEM-FIG. 1

Referring to FIG. 1 there is shown an overall stroboscope control system which includes a power supply 10 that is connected to any appropriate line voltage shortage source, for example. The power supply may be conventional and supplies the various other components of the system with appropriate operating voltages. It supplies in one mode of operation, for

example, the current for a low intensity charging circuit 11 which is connected to one electrode of a stroboscope lamp such as the General Electric Type H-151 lamp. In another mode, the power supply 10 is connected through a high intensity charging circuit 12 to the same electrode of the lamp 14. The low intensity charging circuit 11 is used when it is desired to illuminate the lamp 14 at a predetermined flashing rate in synchronism with rotation of the device under study by the stroboscope. The high intensity charging circuit 12 is switched in series with the lamp 14 when, instead of producing a multiplicity of flashes of light, it is desired to take a single photograph of the rotating device at a very high intensity of light.

An ionizing voltage circuit 13 is also provided which is connected to the trigger winding 15 associated with the lamp and, when the winding is energized at the desired time, fires the lamp. The ionizing circuit 13 may be entirely conventional. Its function is to step-up the relatively low level voltage appearing at its input from switch 19 to a much higher amplitude, say on the order of 10,000 volts, for firing the strobe lamp 14. It accomplishes this, for example, by controlling the discharge of a charging capacitor connected to power supply 10 through the primary of an output transformer having a very high secondary-to-primary turns ratio.

There is also provided a frequency dividing circuit 16 whose input may be connected to a source of external synchronizing signals associated with the rotating device under study. When the frequency of the external pulses is much higher than the rate at which the lamp 14 can flash, it is the function of the frequency divider 16 to supply pulses to the ionizing voltage circuit 13 at a submultiple of the frequency or repetition rate of the external sync signals. Unless the frequency of these input synchronizing pulses (which are generated in response to rotation of the device under study) is converted to a synchronous lower one, the stroboscope lamp 14 will either stay on continuously or not flash at all. Unlike prior stroboscope control circuits, the circuit 16 need not be manually set to a predetermined division ratio depending upon the frequency of the incoming sync pulses but rather accomplishes this automatically.

The output of the frequency dividing circuit 16 may be applied to a delay circuit 18 through a switch 17 and thence, through switch 19, to trigger the ionizing circuit 13. Alternatively, the output may be applied directly through switches 17 and 19 to the ionizing circuit. The delay circuit route is used when it is desired to shift the time of occurrence of the stroboscope flash to a desired point in selected cycles of rotation of the device under study. The delay circuit is bypassed when the frequency-divided sync pulses are to be applied directly to trigger the ionizing circuit 13.

Under certain circumstances, it may be desired to take a photograph of the device under study by means of a single, high intensity light flash. This is accomplished by using the high intensity timing circuit 20 when the camera shutter generates the desired signal. Immediately thereafter, the high intensity circuit 20 disables the switch 19 from transferring signals from either the delay circuit 18 or the dividing circuit 16 to the ionizing circuit. This is done to prevent harm to the contacts of the high intensity charging circuit due to a very high current surge that might be caused by the application of a trigger pulse to the lamp 14 just when switch contacts in the circuit 12 are closing.

FREQUENCY DIVIDING CIRCUIT 16-FIG. 2

As stated previously, if the device under study is rotating or operating at a very high cyclic rate in excess say, of 200 c.p.s., the lamp 14 may not flash at all or may stay on continuously. It is therefore necessary to reduce the frequency of the synchronizing signals derived from the device under study to a frequency within the operational range of the lamp 14. The circuit 16 is so designed as to reduce the effective synchronizing signals to a frequency less than 200 c.p.s., although with different values of components this circuit can be modified to operate at any other maximum input signal frequency.

The external synchronizing signals may be derived in any conventional manner from the operation of the object under test. For example, they could be generated by a shutter attached to the moving part which interrupts the path of light from a light source to a photoelectric cell, or they could be generated by a set of contacts which open and close once for each revolution of a rotating shaft, etc. These external sync signals, which can be sinusoidal or pulselike, for example, are applied by a coupling capacitor 25 to the anode of diode 26 which passes only positive pulses. Capacitor 25 and resistor 28 cooperate to shape the incoming sync signals somewhat. The sync signals are then applied to the C gate electrode 27c of a silicon controlled switch indicated generally at the numeral 27. The A electrode 27a is connected through a voltage-dropping resistor 29 to a source of B+ voltage which may be the power supply 10, for example. A secondary winding 30b of a transformer indicated generally at the numeral 30 is connected to the A gate electrode 27b and to one end of the resistor 29. A load resistor 32 is positioned between the C electrode and ground. The resistor 31 serves to establish a predetermined potential difference between the cathode gate 27c and the cathode 27d.

The silicon control switch, as is well known, can be turned on by a pulse of the proper polarity applied to the cathode gate electrode 27c and turned off by a pulse of the same polarity applied to the anode gate electrode 27b. The first positive sync pulse will turn on switch 27 so that current will flow from B+ through the switch to ground producing a voltage drop across the resistor 32. The value of the load resistor 32 is chosen to allow enough current to flow through the switch to keep it in the conductive state. As a result of the flow through the switch 27, a positive pulse will be propagated through the capacitor 34 and across the output resistor 35 to the switch 17. When the switch 27 is rendered conductive, current will also flow into a timing circuit which comprises the unijunction transistor 36, the resistors 37 and 38, and the timing capacitor 39. The value of resistors 37 and 38 and of the capacitor 39 determine the maximum output frequency of the frequency dividing circuit. When sufficient current flows through the resistors 37 and 38 into the capacitor 39 to charge the latter to a predetermined level, the unijunction transistor 36, which is normally nonconductive, will turn on and the capacitor will discharge through it and the transformer primary winding 30a to ground. The timing circuit is isolated from the cathode of switch 27 by the resistor 40. The windings 30a and 30b are mutually coupled, but the winding 30b is arranged to produce an induced voltage of the same polarity. This induced voltage will turn off the switch 27. Thus, the first positive sync pulse will start the flow of current through switch 27 but from that time on to the end of the timing cycle the circuit 16 operates independently of the receipt of intervening external sync signals. The switch 27 stays on only as long as the time constant of the timing circuit permits. Consequently, the very high repetition rate of the sync pulses from the object under study is effectively reduced to a rate which is within the operating (flashing) range of the strobe lamp.

SWITCH 19

If the switch 17 is in the "delay-off" condition, the frequency-divided pulses from circuit 16 will be bypassed around the delay circuit 18 and applied to a switch 19 (FIG. 3). Switch 19 includes sets of contacts 43 and 44 which are normally closed and 45 and 46 which are normally open. These sets of contacts are operated by energization and deenergization of the winding 42 (FIG. 6) as will be explained below. In addition, there is a voltage-dropping resistor 47 connected between ground and one of the contacts of the set 45. With the switch 17 in the "delay-off" position, therefore, the frequency-divided pulses will be applied via switch contacts 44 and 43 to actuate the ionizing voltage circuit 13 which supplies the trigger coil 15 with the trigger voltage.

DELAY CIRCUIT 18-FIG. 5

When the flashing of the strobe lamp 14 does not occur at the desired times in the rotation cycles of the object under test, the delay circuit 18 can be used to vary the phase of the frequency-divided signals from circuit 16 before they are applied to the ionizing voltage circuit 13. With the switch 17 in the "delay-on" position, the positive-going output pulses of circuit 16 developed across load resistor 35 are applied via diode 55 to the C-gate electrode 56c of silicon control switch 56. The switch 56 is so biased that this positive pulse will turn it on so that current will flow from B+ through voltage dropping resistor 57 and load resistor 58 to ground. The current through the switch 56 is sufficient to keep it on and the voltage developed across resistor 58 will be applied to a timing circuit comprising unijunction transistor 60, resistor 61, variable resistor 62, and timing capacitor 63. The voltage on the capacitor 63 will build up at a rate and to an extent determined by the RC constant of the resistor 61 and the setting of resistor 62, and the capacitor 63. At the end of the timing cycle, the capacitor 63 discharges through the transistor 60 and the primary winding 65a of the transformer 65 to ground. Since the winding 65a is mutually coupled to the secondary winding 65b, there will be a positive pulse induced in the winding 65b and applied to the A gate 56a thereby turning off the switch 56. At the same time, a pulse is induced in another secondary winding 65c connected to switch 19 for eventual application to the ionizing circuit 13 for triggering the strobe lamp. Within limits the variable resistor 62 may be adjusted to produce output pulses delayed by a time not exceeding the interpulse time of the frequency-divided pulses.

SWITCH 19-FIG. 3

The frequency-divided pulses may be applied directly to the switch 19 or may be delayed in circuit 18 and then applied to the switch 19. The switch 19 serves to distribute the delayed or undelayed frequency-divided sync pulses to the ionizing circuit 13. As will be explained later, when a photograph is to be taken, it also cooperates with the high intensity circuit 20 to prevent the application of any triggering pulses to the coil 15 in the interval between complete inactivation of the low intensity circuit 11 and complete activation of high intensity circuit 12. This is done to protect switch contacts in those respective circuits from the effects of unduly large current surges in that interval.

Whenever the high intensity circuit is not on, the sets of contacts 43 and 44 are closed. This enables the frequency-divided pulses, delayed or not, to be applied to the ionizing circuit for triggering the lamp 14. At the same time the sets of contacts 45 and 46 are open so that no pulse from the high intensity circuit 20 can be applied to circuit 13. The states of the sets of contacts in the switch 19 (and of the contacts 51 and 53 in circuits 11 and 12 respectively) are changed by energization of coil 42 in the circuit 20, as will be explained later, when the circuit 20 is brought into service for taking a single photograph of the illuminated object under test. Resistor 47 is used to develop a voltage pulse when the contacts 45 and 46 are closed.

LOW INTENSITY CHARGING CIRCUIT-FIG. 4

Normally, this circuit is operating to supply the voltage across lamp 14 necessary to enable its being flashed repeatedly when the coil 15 is energized in response to the sync pulses. The voltage produced across lamp 14 is sufficient to produce low intensity flashes adequate for visual observation. The circuit 11 is supplied with a voltage from the power supply through choke coil 49 and normally closed contacts 51. This voltage charges the relatively small charging capacitor 50 so that voltage builds up across this capacitor up to a predetermined level whereupon it discharges through the lamp 14. The current passing through the lamp 14 is of relatively low intensity, but is entirely adequate for repetitive flashing of the ob-

ject under study at frequencies up to 200 c.p.s., for example, depending upon the values of the circuit's components. When, however, a photograph is to be taken, the contacts 51 are opened in response to energization of coil 42 and the contacts 53 of the high intensity timing circuit 20 are simultaneously closed.

HIGH INTENSITY TIMING CIRCUIT 20-FIG. 6

It is often desired to obtain a photograph of the object under study by the strobe illumination. To do this, the circuit 20 is provided which can be activated at any time without previously disabling the frequency-dividing circuit 16 or the delay circuit 18. However, because of the damage that might be done to the set of contacts 53 in the circuit 12 if the ionizing circuit 13 is actuated by a sync pulse before contacts 53 are fully closed, the circuit 20 must have special features. The circuit 20 cooperates with the switch 19 and with the contacts 51 and 53 to insure that no sync pulses are applied to the ionizing circuit for triggering the coil 15 until such time as the set of contacts 53 have been completely closed. Were this not the case, since the charging capacitor 52 of the high intensity charging circuit has such a large value, the voltage across the contacts just before the "make" of contacts 53 would produce a very high current arc between these contacts and weld them together or otherwise destroy them.

Accordingly, whenever a photograph is to be made, the actuation of the shutter of the camera synchronously closes the switch 70. Thereupon the voltage at point A goes to ground potential as shown in FIG. 8, Part A and current from B+ passes through the switch-actuating coil 42 to ground. Energization of coil 42 starts the closure of contacts 45, 46 and 53 but since the switch 19 is an electromechanical device a finite period of time, say, 10-20 milliseconds, will elapse before complete closure is effected. The switch contacts 45, 46, and 53, as well as the contacts 43, 44 and 51 respectively open and begin and close simultaneously. The switch or relay may be of the type having three movable arms, each with contacts mounted on both sides at the end, which move between two sets of contacts, each set having three contacts. The broken line 42a indicated the magnetic coupling the coil 42 to the various contacts controlled by it.

Ordinarily, the transistor 71 is conducting but the current through the coil effectively shorts out resistors 74 and 86 and cuts off the transistor. Consequently, a pulse if generated from B+ (FIG. 8, Part B) which goes through the resistor 88, coupling capacitor 72 and diode 73 to switch 75. This positive pulse can not yet be transferred to the ionizing circuit through capacitors 81 and 83 because the switch contacts 45 and 46 are now open. This pulse is applied to the cathode gate of silicon control switch 75 after being delayed somewhat by the capacitor 72 and resistor 77.

Upon application of this pulse to the switch 75, the latter begins to conduct to ground through load resistor 78 (FIG. 8, Parts C and D). A charging voltage is produced that is applied to the resistor 82 and the capacitor 84 which constitute the RC portion of the timing subcircuit. Resistor 80 isolates the timing circuit from the cathode of switch 75. While the timing circuit is charging up, the contacts 45 and 46 finally close (FIG. 8, broken line 'sc). However, since the transistor 75 is still conducting, the positive pulses at F still do not produce corresponding pulses at G (see FIG. 3) since there is a common power supply 10 for the circuit 20 and for the frequency-dividing and/or delay circuits 16 and 18, whichever is the source of pulses at G.

When the voltage finally builds up to a predetermined point determined by the RC constant, on the order of say, 50 milliseconds, the capacitor 84 will discharge through the unijunction transistor 85 and the winding 87a to ground. The passage of this current (FIG. 8, Part E) through winding 87a will induce a positive pulse in the coil 87b which is connected between anode and anode gate of the switch 75, thereby turning the latter off and completing the timing cycle (FIG. 8, Part C+D, broken line t=1).

Thus, any pulses which have appeared at the input to switch 19 (FIG. 8, Part F) between the time that the flash synchroniz-

ing switch 70 closes and the end (t=1) of the timing cycle cannot be transferred to the ionizing circuit. Consequently, there is no danger to the contacts 45 and 46 due to the arrival of a pulse at the input to the ionizing circuit just as contacts 53 are about to close. As soon as the contacts 45, 46 and 53 have been closed, the next positive pulse 95 (FIG. 8, Part F) from the delay circuit or from the frequency-dividing circuit will be transmitted via closed contacts 46 through the capacitor 83 and the diode 73 to the cathode gate of switch 75 thereby causing it to conduct and start another timing cycle 96 (FIG. 8, Part C+D). The increase in the positive potential at D is transmitted via capacitor 81 and newly close contacts 45 to ionizing circuit 13 to trigger lamp 14 "on" for a high intensity flash since capacitor 50 is then in circuit with the lamp.

HIGH INTENSITY CHARGING CIRCUIT 12-FIG. 7

Whenever a coil 42 is energized upon closure of the switch 70, the switch contacts 53 will close and contacts 51 will open so that only the capacitor 52 is in circuit between the power supply and the lamp 14. The value of the capacitor 52 is much greater than that of the capacitor 50. For example, it may be on the order of 125 times as large. Consequently, a much higher voltage will be built up across it, which, when the contacts 53 are closed, will produce a much greater current to the phototube resulting in a much higher light intensity for photographic purposes. The circuit 20 is provided to prevent damage to contacts 53 when they just are about to close due to the large current that might be drawn should the lamp 14 fire at this time.

GENERAL REMARKS

While the circuit components of the present invention may have different values depending upon the flash lamp used, or on the input synchronizing signal frequency, or on the amount of delay desired, or the characteristics of the associated camera, one set of component values which has proved to be entirely satisfactory is set forth below:

Component No.:	Value
40 25	mfd .0022
26	1N2071
27	3N58
28	K ohms 10
29	ohms 12
31	K ohm 1

90	ohms 390

It should also be understood that the system may be used with internally generated synchronizing signals rather than those generated by couplings to the device under test. This would require certain modifications of the circuit but this does not affect the operation of the present invention in any material way.

While the invention and its various novel subassemblies and subcircuits have been described with reference to a stroboscope system, it is evident that the overall system and the novel subcircuits could find utility in other applications. For example, the frequency division circuit has broad utility as does the delay circuit. Furthermore, the high intensity timing circuit conceivably could be used in other applications where it is desired to produce a switching or delaying action for signals.

Still other variations and applications will occur to one skilled in the art upon perusal of this specification and the drawings herein which do not depart from the essence of the invention. Consequently, it is desired that this invention be limited solely by the claims herein:

I claim:

1. A system for controlling a stroboscope comprising:

a stroboscope lamp,

first means for supplying a large current for flow through said lamp,

second means for supplying a relatively small current for flow through said lamp,

switching means for coupling only one of said or first and

second means to said lamp at any time, said switching

means normally coupling said second means to said lamp, third means to which synchronizing signals at a first frequency are applied for producing output signals which have a second frequency lower than said first frequency and are within the operating range of said lamp,

fourth means for applying said output signals to trigger said lamp, and

fifth means adapted to be coupled to photographic apparatus and coupled to said switching means for causing the latter to decouple said low current-supplying means

and couple said high current-supplying means to said lamp in response to actuation of said photographic apparatus, said fifth means also acting to disable said fourth means until after said switching means has completely

coupled said high current-supplying means to said lamp.

2. The control system according to claim 1 wherein said fourth means also includes means for adjustably delaying said output signals before applying them to trigger said lamp.

5

3. A system for controlling the flashing of a stroboscope lamp comprising:

first current supply means for supplying a relatively large current for flow through said lamp,

second current supply means for supplying a relatively small current for flow through said lamp,

switching means for coupling only one of said first and second current supply means to said lamp at any time, said switching means normally coupling said second current supply means to said lamp,

means for supplying regularly repetitive signals to trigger said lamp when said switching means is in its normal coupling condition, and

means for supplying a nonrepetitive signal to trigger said lamp, said means also including means for causing said switching means to couple said first current supply means to said lamp during the occurrence of said nonrepetitive signal said nonrepetitive signal supply means including means for preventing the supplying of any signals to trigger said lamp during the interval in which said switching means is changed from its normal coupled condition to its condition in which it couples said first current supply means to said lamp.

4. The system according to claim 3 wherein said regularly repetitive signal supply means including means for automatically reducing the frequency of input signals whose frequency is in excess of the flashing range of said lamp to a lower frequency within said range, said lower frequency signals thereupon being supplied as said repetitive signals to trigger said lamp.

5. A system for controlling the flashing of a stroboscope lamp including:

a first current source being coupled to said lamp and being adapted to provide a current thereto of a first value;

a second current source being coupled to said lamp and being adapted to provide a current thereto of a second value;

switching means for applying a selected one of said first and said second current sources to said lamp at any one time, said switching means being normally applying said second current source to said lamp;

first trigger means for supplying regularly repetitive signals to trigger said lamp when said switching means is in its normal condition; and

second trigger means for supplying a nonrepetitive signal to trigger said lamp, said second trigger means including means for causing said switching means to apply said first current source to said lamp during the occurrence of the nonrepetitive signal.
